Inventor

UNITED STATES PATENT OFFICE.

MELVILLE BEACH, OF ASHTON, ILLINOIS.

HUB-WRENCH.

SPECIFICATION forming part of Letters Patent No. 431,641, dated July 8, 1890.

Application filed May 6, 1890. Serial No. 350,757. (No model.)

To all whom it may concern:

Be it known that I, MELVILLE BEACH, a citizen of the United States, residing at Ashton, in the county of Lee and State of Illinois, have 5 invented a new and useful Hub-Wrench, of which the following is a specification.

This invention has relation to hub-wrenches, and among the objects in view are to provide an exceedingly simple and powerful wrench 10 adapted for clamping and rigidly connecting the hub-band of a wheel with the axle-nut, whereby said wheel may be removed and replaced simultaneous with the nut for the purpose of oiling, cleaning, or repairing the bearing. 15

With the above general objects in view the invention consists in certain features of construction, hereinafter specified, and particularly pointed out in the claims.

20 In the drawings, Figure 1 is a transverse section of a hub and its axle, a wrench constructed in accordance with my invention being applied thereto and shown in side elevation. Fig. 2 is a perspective of the wrench in 25 detail. Fig. 3 is a perspective, in detail, of the binding member. Fig. 4 is a similar view, in detail, of the opposite member.

In practicing my invention, I construct the wrench of two opposite sections or members, 30 which are of substantially semicircular shape, and intermediate their ends are pivoted.

1 represents the binding-section, and 2 the clamping-section, and through the two is passed a pivot-bolt 3. The adjacent faces of 35 the two sections are perfectly plain where they have contact with each other, so as to permit them to slide readily one upon the other. The inner ends of the sections are provided with transverse jaws 4, the inner sides 40 of which are provided with recesses 5, which receive the upper edges of the opposite section, and thus serve to maintain said sections in sliding contact with each other. The outer ends of the section 1 terminate in a perforated

45 head 6, the perforation being threaded, and in the same is mounted a binding-screw 8, the inner end of which projects through the opposite side of the perforation and is provided with a loose washer 9, which may or may not 50 be provided with a felt or other covering 10. The outer end of the opposite member is pro-

vided with a laterally-disposed head 11, the opposite extremities of which are provided with threaded openings 12, arranged at an angle with relation to each other, and in the 55 openings are mounted set-screws 13, having at their inner ends loose washers 14, covered or not by pads 15.

16 designates the hub of the wheel; 17, the axle; 18, the nut; and 20, the hub-band. To 60 apply the wrench, the outer ends of the members are introduced over the hub-band and the inner jaws over the axle-nut, and said members are adjusted to a proper relative position with regard to the nut and the diameter of the hub-band through the medium of the binding-screws 13. After such adjustment, the screw 8 is manipulated so as to tightly bind upon the hub-band, and in so doing the outer ends of the members are laterally spread and the inner ends or jaws contracted and clamped upon the nut. It will now be apparent that both the nut and the hub are rigidly connected, and by using the wheel as a leverage and rotating to the rear 75 the nut is removed from the axle, which latter may be cleaned, oiled, repaired, or otherwise attended to, and the wheel replaced by simply introducing the hub over the axle and giving the wheel a few turns. In this way 80 the wheel may be removed and replaced without separating the nut from the wheel or being obliged to lay the same down to become filled with sand and grit or soiling the clothes and hands of the operator. 85

Having thus described my invention, I claim—

1. In a wrench, the combination, with two curved members pivoted together intermediate their ends, the inner extremities of said members being provided with nut-receiving jaws and the outer extremities of said members with threaded openings, of binding-screws mounted in the openings, substantially as specified. 95

2. In a wrench, the combination, with the oppositely-curved members pivoted together intermediate their ends, the inner ends of said members terminating in laterally-disposed nut-receiving jaws, each of which is recessed 100 at its inner edge to receive the upper edge of the opposite member, and the outer ends of

which are provided with threaded openings, of binding-screws mounted in the openings, substantially as specified.

3. In a wrench, the combination, with opposite semicircular members pivoted together intermediate their ends and terminating at their inner ends in laterally-disposed jaws, one of said members terminating at its outer end in a threaded and perforated head and the opposite member at its corresponding end in a transverse head perforated at its opposite ends and at an angle to each other, of binding-screws mounted in the perforations, substantially as specified.
- 15 4. In a wrench, the combination, with opposite semicircular sections pivoted intermediate their ends and terminating at their inner ends in laterally-disposed nut-receiving jaws, the outer edges of which are recessed to receive the outer edges of said jaws, the outer end of one jaw terminating in a head having a single-threaded perforation and the

outer end of the opposite jaw terminating in a laterally-disposed head having opposite angularly-disposed threaded openings, set-screws mounted in the openings and in the single perforation, loose washers mounted on the set-screws, and pads upon the inner faces of the washer, substantially as described.

- 25 5. In a wrench, the combination of two curved members pivoted together intermediate their ends, the inner extremities of said members being provided with nut-receiving jaws and the outer extremities of said members being provided with clamping devices to engage the hub-band, substantially as specified.

In testimony that I claim the foregoing as my own I have hereto affixed my signature in presence of two witnesses.

MELVILLE BEACH.
